UNITED STATES PATENT OFFICE

ALFRED ARMSTRONG EDWARD PENNEFATHER, OF TIMARU, NEW ZEALAND

HANGER AND PRESS FOR GARMENTS AND OTHER ARTICLES

Application filed October 31, 1929, Serial No. 403,878, and in New Zealand August 28, 1929.

This invention relates to hangers and presses for garments such as coats and trousers, and has for its object generally, the provision of an improved device for hanging coats, vests, and trousers, the particular object of the invention being to provide a form of hanger, having incorporated therein suitable means for stretching and pressing trousers, and which may be conveniently collapsed and packed, in a suitcase or the like, without occupying undue space, or adding materially to the weight and bulk of the travelling equipment.

According to the invention, the improved device comprises clamping means for articles to be pressed and stretched; guide members adapted to be extended from said clamping means; a rod over which articles gripped by said means are folded, adapted to be moved and held in said guides to stretch said articles, and a hanger on which other articles can be hung, attached to said rod, for suspending the device and its load.

The invention is illustrated in the accompanying drawings, and will be more particularly described in conjunction therewith,

Fig. 1 being an elevation showing the complete device extended or opened for use, while

Fig. 2 is an end view of the device as represented in Fig. 1,

Fig. 3 showing the device collapsed or folded for packing or stowing away, while

Fig. 4 is a detail cross sectional view (enlarged) on the line A—A Fig. 1,

Fig. 5 is a part elevation, and

Fig. 6 an end view illustrating a modified form of the device.

A centre bar 1 has projecting from one side a pair of screw threaded studs 2, and from the opposite side a pair of screw threaded studs 3, the latter being closer together than the studs 2. A bar 4 the same length as the bar 1, is slotted at 4^a to pass upon the studs 2, while a shorter bar 5 slotted at 5^a is capable of being passed upon the studs 3, wing nuts 6 and 7 being placed on the studs 2 and 3 respectively to enable the bars 4 and 5 to be clamped to the centre bar 1.

The slots 4^a and 5^a are made to open

tate the passing of the latter upon the studs 2 and 3, and where the wing nuts 6 and 7 bear against the bars 4 and 5, the latter are faced with metal plates 8 slotted to conform to the slots 4^a and 5^a, to prevent wear of said bars.

Hinged to the ends of the centre bar 1 at 9^a are guide members 9, each guide member containing a slot 10 having an enlargement 11 at its lower end and opening into side recesses 12 at its upper end.

Stays 13 pivoted at one end to the centre bar 1, and hooked at the other end to engage projections 14 from the guide members 9, are provided for the purpose of holding said members 9 in extended or opened position as illustrated in Fig. 1.

A rod 15 having its ends projecting outwards through the slots 10 in the guide members 9, has mounted thereon a roller 16 located between said guide members and is provided with collars 17 outside the latter.

Short lengths 18 of chain or other flexible means detachably engaged with rings 19 through said collars 17, are connected to the 75 extremities of a collapsible wire hanger 20, provided at its centre with a hook 21.

In order to press and stretch a pair of trousers, the latter are folded along the front and back creases, in the usual way, and with the rod 15 entered in the lower or inner recesses 12 in the guide members 9, the folded waist or upper wide portion of the trousers is gripped between the centre and outer bars 1 and 4, the trousers then being folded over 80 the roller 16 on the rod 15, and returned to the clamping means, so that the bottoms of the trouser legs can be gripped between the centre bar 1 and the shorter bar 5.

With the trousers folded, and firmly 90 gripped between the bars 1, 4 and 5, the rod 15 is forced outwards in the guide members 9, or away from the clamping means, to stretch the trousers, the tension being maintained on the latter by entering the ends of 95 the rod 15 in the upper or outer recesses 12.

Other articles, such as a coat and vest, can be placed on the hanger 20, and the device with the articles thereon suspended by the hook 21 from a suitable fixture.

In order to collapse or fold the device for packing in a suitcase or elsewhere, the rod 15 is lowered in the guide members 9, and the collars 17 brought inwards through the enlargements 11 in said members to enable the rod 15 to be accommodated in the hollow upper edge 1^a of the bar 1, following which the stays 13 are disengaged from the members 9, and dropped between the centre bar 1 and the short bar 5.

This leaves the members 9 free to be turned down one over the other on top of the bar 1 with the rod 15 therein, the hanger 20 then being collapsed and accommodated between 15 the bars 1 and 4.

Upon the wing nuts 6 and 7 being tightened and a securing band 22 placed around the folded device, the latter is in the form of a compact package, as shown in Fig. 3, capable 20 of being easily stowed in a suitcase or the like without taking up undue space, or materially increasing the weight thereof.

In the modification illustrated in Figs. 5 and 6, the slotted guide members 9 are formed 25 of wire and each member has at its lower end an arm 23 adapted when the member is brought to the open or extended position, to engage in a spring catch 22 on the centre bar 1, for the purpose of retaining the member in such open or extended position.

Also each wire member 9 has formed in its upper or outer end an inward bend or kink 24, in which eyebolts 25 swivellable in the ends of the rod 15 carrying the roller 16 and slideable on the wire of the members 9, are adapted to rest, in order to maintain the rod and roller at the outer ends of the members 9, when placing trousers over said rod and roller.

40 The chains 18 of the hanger 20 are attached to the eyebolts 25, and upon the device being hung by the hook 21, said eyebolts pass upwards into corners 26 of the members 9, and cause a tension to be placed on the trousers which are folded over the rod 15 and roller 16 and gripped by the clamping bars 1, 4 and 5.

Owing to the eyebolts 25 swivelling in the ends of the rod 15 the latter can be dropped 50 into the hollow upper edge 1^a of the bar 1, and the members 9 folded thereover without disconnecting the rod from said members.

What I do claim and desire to obtain by Letters Patent of the United States of 55 America is:—

1. A device for the purpose set forth comprising clamping means for articles to be pressed, guide members adapted to be extended from said clamping means, a rod 60 over which particles gripped by said clamping means are folded adapted to be moved and held in said guide members to stretch said articles, a hanger on which other articles can be placed attached to said rod for suspending 65 the device and its load, said clamping

means comprising a center bar having screw threaded studs thereon, outer bars and wing nuts upon said studs and said center bar being formed with a hollow upper edge to accommodate said rod over which the articles are 70 folded.

2. A device for the purpose set forth comprising clamping means for articles to be pressed, guide members to be extended from said clamping means, a rod over which 75 articles gripped by said means are folded adapted to be moved and held in said guide members to stretch said articles, collars upon said rods, a hanger upon which other articles can be placed attached to said rod for suspending the device and its load, said hanger being collapsible and detachably connected with the rod by short lengths of chain engaging rings in the collars upon the rod end.

3. A device of the class described comprising clamping means for articles to be pressed and stretched, guide members adapted to be extended from said clamping means, a rod over which articles gripped by said means are folded, said rod being adapted to be 80 moved and held in said guide members to stretch said articles, a hanger upon which other articles may be placed attached to said rod for suspending the device and its load, said guide members being slotted to receive 85 the end of said rod and said guide members containing recesses for receiving the rod end, collars upon the ends of said rods to maintain said guide members and rod in position and also enlargements in said slotted guide members through which said collars on the 90 rod can be passed.

4. A device of the class described comprising clamping means for articles to be pressed and stretched, guide members adapted to be 105 extended from said clamping means, a rod over which articles gripped by said means are folded, said rod being adapted to be moved and held in said guide members to stretch said articles, a hanger upon which other articles may be placed attached to said rod for suspending the device and its load, said guide members being hinged to said clamping means to fold over the same and stays to hold 110 said guide members in their open or extended positions.

5. A device of the class described comprising clamping means for articles to be pressed and stretched, guide members adapted to be 120 extended from said clamping means, a rod over which articles gripped by said means are folded, said rod being adapted to be moved and held in said guide members to stretch said articles, a hanger upon which other articles may be placed attached to said rod for suspending the device and its load, said rod having a roller thereon between said guide members and collars upon said rod outside said 125 guide members and a hanger flexibly connected to the ends of said rod.

6. A device of the class described comprising clamping means for articles to be pressed and stretched, guide members adapted to be extended from said clamping means, a rod
5 over which articles gripped by said means are folded, said rod being adapted to be moved and held in said guide members to stretch said articles, a hanger upon which other articles may be placed attached to said rod
10 for suspending the device and its load, spring catches on a bar of said clamping means, said guide members being provided at their inner ends with arms adapted to engage in said spring catches.
- 15 7. A device of the class described comprising clamping means for articles to be pressed and stretched, guide members adapted to be extended from said clamping means, a rod over which articles gripped by said means
20 are folded, said rod being adapted to be moved and held in said guide members to stretch said articles, a hanger upon which other articles may be placed attached to said rod for suspending the device and its load, said guide
25 members being formed of wire and eye bolts swivelly secured in said rod and said eye bolts being slidable on the wire of said guide members.
8. A device of the class described comprising clamping means for articles to be pressed and stretched, guide members adapted to be extended from said clamping means, a rod over which articles gripped by said means
30 are folded, said rod being adapted to be moved and held in said guide members to stretch said articles, a hanger upon which other article may be placed attached to said rod for suspending the device and its load, and said guide members being inwardly
35 directed at their outer ends.
- 40

In testimony whereof I have signed my name to this specification.

ALFRED ARMSTRONG EDWARD PENNEFATHER.
